DRAFT GEAR FOR RAILWAY DRAFT RIGGING

Eric G. Forssell, Kenmore, N. Y., assignor to W. H. Miner, Inc., Chicago, Ill., a corporation of Delaware

Application July 18, 1955, Serial No. 522,687

6 Claims. (Cl. 213—45)

This invention relates to draft gear for railway draft 15
rigging.

It is a main object of the invention to provide, in a
draft gear that has a resilient column encased in a metal
casing, an improved plunger and front follower by which
the gear is held together as a unit and through which pres- 20
sure is applied to the column.

Another object of the invention is to provide a pressure
applying plunger for a draft gear, composed of two identical
members which telescope together to permit insertion
in the casing of the gear and are spread apart and
held in spaced apart relation to lock the gear together as 25
a unit.

Another object of the invention is to provide an im-
proved front follower for the resilient column of a draft
gear, which follower carries means interengaged with the
members of a two-piece pressure applying plunger to hold
those members in position to lock the gear together as a 30
unit.

Further objects of the invention not specifically men-
tioned here will be apparent from the detailed descrip- 35
tion and claims which follow, reference being had to the
accompanying drawings in which the preferred embodiment
of the invention is shown by way of example and in
which:

Figure 1 is a front end elevational view of the com- 40
pletely assembled gear;

Figure 2 is a plan view of the gear;

Figure 3 is a cross sectional view taken substantially 45
along the line 3—3 of Figure 1, looking in the direction
of the arrows;

Figure 4 is a side elevational view of the lower plunger
member;

Figure 5 is a side elevational view of the upper plunger
member;

Figure 6 is an end view of the gear showing the plunger
members telescoped together for insertion in the casing;

Figure 7 is a view of the upper plunger member as seen
from the front end of the gear;

Figure 8 is a view similar to Figure 7, showing the
lower plunger member;

Figure 9 is an elevational view of the plunger member
as seen from the line 9—9 of Figure 7;

Figure 10 is a cross sectional view taken along the
line 10—10 of Figure 9, looking in the direction of the
arrows; and

Figure 11 is a cross sectional view along the line 11—11
of Figure 9, looking in the direction of the arrows.

As shown in the drawings, the gear of the present
invention consists of a metallic casing A in which a
resilient column B is housed and stabilized by stabilizing
separators C with a front follower D at the front end
of the column and in engagement with the pressure applying
plunger E.

The casing consists of spaced apart top and bottom
walls 10 and 11 joined by side walls 12 and 13 and closed
at its rear end by a solid rear wall 14. The top wall 10
and bottom wall 11 flare outwardly adjacent the front end

2

of the casing, forming internally opening grooves 15
which are closed at the front end of the casing by in-
wardly turned flanges 16, best seen in Figure 3.

The resilient column consists of a plurality of pads of
known construction, each consisting of a pair of metal
plates with a solid pad of rubber interposed therebetween
and bonded thereto. The units in the column are divided
into groups by stabilizing separators C, also of known
construction and consisting of a plate interposed between
10 adjacent units and around the edges of which are flanges
that have sliding engagement with the walls of the casing.

The front follower D consists of a structure similar to
the stabilizing separators C, having forwardly extending
frusto-conical bosses 20, which are four in number. The
rearwardly extending flanges 21 of the front follower
contain openings 22 and the walls 10 and 11 of the cas-
ing contain openings 23.

The pressure applying plunger consists of two members
which are of identical construction. Each of these mem-
bers consists of a rectangular base 30 whose length is
substantially equal to the inside width of the casing A
and whose width is somewhat less than one-half of the
height of the casing. The base 30 contains a pair of
frusto-conical sockets 31 located symmetrically therein.

Upstanding from one edge of the base 30 and at right
angles thereto is a flat wall 32 from which a rectangu-
lar boss 33 projects outwardly, this boss extending from
near one end of the wall to approximately the median
line of the wall. Wall 32 also contains an inwardly ex-
tending socket 34 which extends from the opposite end
of the wall to approximately the median line thereof.

Upstanding from the base 30 is an inclined side wall 35
and inclined end walls 36 formed integrally with the base
30 and flat wall 32, which side and end walls, together
with the wall 32, are joined by a front wall 37 formed
integrally therewith.

Projecting from the base 30 at the junction of side
wall 35 therewith are lugs 38, which are two in number.

In assembling the gear, casing A is placed with its
closed end lowermost, and the units of resilient column
B and stabilizing separators C are placed therein. The
front follower D is placed at the top of the column and
pressure applied thereto to compress the column suffi-
ciently to align the openings 22 in the flange 21 of the front
follower with the openings 23 in the walls of the casing.
45 Suitable keys, not shown, are inserted through these open-
ings to hold the follower against the pressure of the thus
compressed resilient column.

The two members of the plunger E are then fitted to-
gether with the boss 33 of the one unit projecting into the
socket 34 of the other unit. When in this position, the
outer edges of the plugs 38 will clear the flanges 16 at the
front end of the casing, thereby to permit the plunger
to be inserted into the casing. The two members are
50 then spread apart to register the frusto-conical bosses
20 on the front follower with the frusto-conical sockets
31 in the plunger members. This moves the lugs 38 into
the grooves 15 in the casing walls. With the plunger
members thus spread apart, bosses 33 still engage in the
60 sockets 34 in the manner shown in Figure 3.

Pressure is then applied to the plunger to relieve the
pressure on the keys which are removed, and as pressure
is removed from the plunger the resilient column B ex-
pands, forcing the lugs 38 into engagement with the in-
turned flanges 16 at the forward ends of the grooves 15,
65 thereby to lock the gear together as a unit. In Figure 3,
the gear is shown in the position which it occupies when in-
stalled in the yoke and pocket of a draft rigging. It will
be noted that the lugs 38 are spaced rearwardly of the
flanges 16 under these conditions.

In operation, pressure is applied to the plunger to tele-
scope it in the casing, thereby to compress resilient col-

umn B, the lugs 38 traveling rearwardly in grooves 15 during this movement. This telescoping movement of the plunger is guided by the flanges 21 on the front follower, which flanges have sliding engagement with the walls of the casing. When the pressure upon the plunger is removed, the resilient column B expands, moving the plunger outwardly of the casing.

Having thus complied with the statutes, and shown and described a preferred embodiment of my invention, what I consider new and desire to have protected by Letters Patent is pointed out in the appended claims.

What is claimed is:

1. The combination with a draft gear in which a resilient column is encased in a metallic casing of rectangular cross section closed at its rear end and open at its front end, which casing includes grooves opening inwardly adjacent its open end, which grooves are closed by flanges at the open end of the casing; of a pressure applying plunger for said resilient column comprising two identical members fitted one above the other in the open end of the casing, each of said members comprising: a rectangular base; a side wall upstanding out of said base at right angles thereto; a boss extending out of said wall and extending from one end to approximately the center of the wall, there being a socket in said wall extending from said boss to the other end of said wall; side and ends on said plunger integral with said base and side wall, and extending forwardly from the base; a front wall on said plunger integral with said wall, side and ends, and parallel to said base; lugs projecting from said base at the junction of said side therewith and extending into said

grooves in the casing; a front follower for said resilient column; and interengaging means on said follower and the bases of said members for holding the members in position with respect to each other and to the follower.

5 2. A device as specified in claim 1, in which the width of the base of the plunger is less than one-half of the height of the casing and in which the interengaged means holds the members apart so that the plunger has sliding fit in the casing.

10 3. A device as specified in claim 1, in which the members are positioned in the open end of the casing with the boss in one member projecting into the socket in the other member and in which the interengaged means spaces the members apart vertically in the casing.

15 4. A device as specified in claim 1, in which the grooves in the casing are located in the top and bottom walls thereof and in which the resilient column forces the lugs on the plunger members into engagement with the flanges projecting into the grooves to hold the gear together as a unit.

20 5. A device as specified in claim 1, in which the interengaged means consists of frusto-conical bosses projecting forwardly from the front follower and into frusto-conical sockets in the bases of the plunger members.

25 6. A device as specified in claim 5, in which the front follower contains four forwardly extending frusto-conical bosses and in which the base portion of each plunger member contains two frusto-conical sockets.
